UNITED STATES PATENT OFFICE.

HERBERT G. MACKINNEY, OF PROVIDENCE, RHODE ISLAND.

DESIGN FOR A GEM-SETTING.

SPECIFICATION forming part of Design No. 14,225, dated August 21, 1883.
Application filed June 16, 1883. Term of patent 14 years.

To all whom it may concern:

Be it known that I, HERBERT G. MACKINNEY, a citizen of the United States, residing at Providence, in the county of Providence and State of Rhode Island, have invented and produced a new and original Design for Gem-Settings, of which the following is a specification, reference being had to the accompanying drawings, forming part thereof.

Figure 1 is a view of the base of a gem-setting, with the prongs or jaws removed to show the distinctive features of my design. Fig. 2 is a side view of my newly-designed gem-setting. Fig. 3 is the same as Fig. 1 without engraving.

The leading feature of my design consists in substantially plane surfaces arranged around the upper edge of the base of the gem-setting between the prongs which constitute the jaws, 20 said surfaces inclining downward and outward, and projecting a little beyond the outline of

the base, the projecting portion having rounded edges and presenting the appearance of scallops.

B is the base; P, the prongs forming the jaws of the setting, and between the prongs are the rounded and inclined surfaces S, which form the distinctive feature of my design. The outline of the sides and outer portion of said surfaces is substantially that of the letter U. The said surfaces may be variously engraved or otherwise ornamented.

I claim—

The design for a gem-setting herein shown and described, the same consisting of the inclined surfaces S around the upper edge of the base and between the prongs of the setting.

HERBERT G. MACKINNEY.
